(57) **CLAIM**

We claim the ornamental design of an automobile, as shown and described.

DESCRIPTION

FIG. 1 is a top plan view of an automobile showing our new design;

FIG. 2 is a right side elevational view thereof, the left side being a mirror image of that shown;

FIG. 3 is a rear elevational view thereof;

FIG. 4 is a front elevational view thereof;

FIG. 5 is a right, front perspective view thereof; and,

FIG. 6 is a left, rear perspective view thereof.

The broken line showings are for environmental purposes only and form no part of the claimed design.
